UNITED STATES PATENT OFFICE.

JOSEPH BRADFORD CLEAVER, OF NEW YORK, N. Y.

ACOUSTIC TELEPHONE.

SPECIFICATION forming part of Letters Patent No. 325,500, dated September 1, 1885.

Application filed April 28, 1885. (No model.)

To all whom it may concern:

Be it known that I, JOSEPH BRADFORD CLEAVER, of the city, county, and State of New York, have invented a new and useful Improvement in Acoustic or Mechanical Telephones; and I hereby declare the following to be a full and clear description thereof.

This invention relates to the construction of the telephone with a series of trussing-wires over the front face of the diaphragm, and an anchoring-disk connected therewith by short connecting-wires, the said anchoring-disk forming the anchorage proper for the line-wire.

The invention will be readily understood by reference to the accompanying drawings, of which Figure 1 is a perspective view of one of the improved telephones, showing its line-wire and the improved resonance-resisting cushion. A portion of the side of the telephone-case is broken out in this view to show the wire and cushion arrangement. Fig. 2 is a front face view of the improved telephone. Fig. 3 is a sectional elevation taken on the line $x-x$ of Fig. 2 through one of the anchorage-fastenings of the diaphragm trussing-wires. Fig. 4 is a detail front elevation of the cushion plate or disk, to which the line-wire is anchored through a cushion, and from which short anchorage-wires extend to the trussing-wires of the diaphragm. Fig. 5 is an enlarged sectional detail of the receiving ear-tube and its attachment-piece by which it is attached to the line-wire of the telephone.

The case A has a textile fabric diaphragm, B, secured over a circular aperture made in its front face-plate, a , as in acoustic telephones now in use. These textile diaphragms are of very thin material, and therefore do not furnish sufficient strength for the anchorage of the line-wire, and to provide the requisite strength of anchorage the anchorage or trussing wires C are drawn tightly across and close to the front face of the diaphragm B, and are turned down through the holes a^2 , in the front plate or diaphragm-frame, a , of the telephone-case, and secured at the back of the said face-plate a' . The said anchorage-holes a^2 are made in pairs, say a quarter of an inch apart, more or less, and the trussing or anchorage

wire is passed in through one hole of a pair and out through its mate, so that at each of these anchorages the trussing or anchorage wire C is securely attached to the said front face-plate, a . The trussing-wires C are drawn tightly across the front face of the diaphragm between these anchorages a' , and the branching anchorage-wires D are attached by their front ends to these trussing-wires C, and by their rear or inner ends to a small metallic disk or cushion plate E, to which the line-wire F is attached in the manner presently explained. This disk or cushion plate E has a central aperture through which the line-wire F passes, and concentrically around the said central aperture, and near the edge of the disk E and at equal distances apart, other apertures are made for the short branching or diverging anchorage-wires D.

A cushion, G, of india-rubber, leather, linoleum, or any equivalent or suitable material, is placed on the center of the disk E and on the side of the said disk next the diaphragm, and a central aperture through this cushion-piece permits the line-wire to extend through the said cushion-piece and be secured to the metallic anchorage-plate f on the inside of the said cushion. The connecting-wires D and the attached disk E form a direct tensional connection from the diaphragm B to the next station, and the acoustic effects produced on or by a diaphragm so constructed and attached are of the highest order and of great utility, and by the use of the intervening cushion G all deleterious sounds—such as the aeolian effects of wind, upon the line-wire or storms and other foreign sounds—are excluded from the telephone.

The receiving mechanism of this telephone consists of a bulb, H, of india-rubber or other suitable material, and an ear-tube, I, leading from the said bulb to the ear of the person receiving. The said bulb is placed on the line-wire—i. e., the line-wire F is passed through the said bulb from side to side—and the result of this device is a wonderfully clear delivery of the telephonic sounds through the tube I to the ear of the receiver.

Having described my invention, I claim—

- An anchorage for the line-wire of an acoustic telephone, consisting of a series of trussing

or anchorage wires drawn tightly across the front face of the diaphragm and connected by means of short parallel wires with a metallic disk of a smaller diameter than the diaphragm 5 and placed behind and slightly removed from the diaphragm, the said subdiametered metallic disk forming the anchorage proper for the line-wire.

2. The disk E, the line-wire F, anchor-plate f, and the cushion G, combined with the anchorage-wires D, trussing-wires C, and diaphragm B, substantially as described.

J. B. CLEAVER.
